[57] CLAIM

The ornamental design for a vehicle trailer body, as shown and described.

DESCRIPTION

FIG. 1 is a rear and left side perspective view of our vehicle trailer body;

FIG. 2 is a top view thereof;

FIG. 3 is a left side view thereof;

FIG. 4 is a front view thereof;

FIG. 5 is a rear view thereof; and,

FIG. 6 is a right side view thereof;

It will be understood that the broken line showing of the tires and wheels throughout the drawings is for illustrative purposes only and forms no part of the claimed design.
